UNITED STATES PATENT OFFICE.

JEREMIAH KEITH, OF NEW BEDFORD, MASSACHUSETTS.

IMPROVEMENT IN EYELETING-MACHINES.

Specification forming part of Letters Patent No. 41,303, dated January 19, 1864.

To all whom it may concern:

Be it known that I, JEREMIAH KEITH, a citizen of the United States of America, and a resident of New Bedford, in the county of Bristol and State of Massachusetts, have made a new and useful invention of an improved eyeletting-machine or machinery for fixing metallic eyelets in cloth or other material; and I do hereby declare the same to be fully described in the following specification and represented in the accompanying drawings, of which—

Figure 1 is a side elevation, Fig. 2 a front view, and Fig. 3 a transverse section, of such machine. Fig. 4 is a longitudinal section of its eyelet receiver or hopper and the directing-ports thereof. Fig. 5 is a vertical section of the directing-ports of the reservoir and chute. Fig. 6 is a vertical section of the eyelet-chute.

The nature of my invention consists in the arrangement of one or more directing ports or passages, in manner substantially as described, with the hopper and the chute of the eyeletting-machine, in order that the eyelets may be caused to enter the chute with their wider ends downward; and furthermore, my invention consists in a combination of the following elements—that is to say, first, the eyelet pin; second, a mechanism for feeding the eyelets to the pin; third, a mechanism for upsetting them; fourth, a mechanism which will perform the functions of holding the eyelet-pin down while an eyelet is being fed upon the pin-anvil, and subsequently operating to elevate the eyelet-pin or effect its elevation through the eyelet, as specified.

In the drawings, A is the frame of the machine. b is the eyelet-anvil, and c the eyelet-pin, which rests on a spring, d, and is applied to the anvil, so as to be capable of playing vertically therein.

The eyelet stamp or upsetter is shown at e. It plays vertically within the frame A, and carries a punch, f, which operates to punch in the cloth or material the holes for reception of the eyelets, such cloth or material to be eyeleted being placed on another anvil, g, arranged underneath the said punch, in manner as shown in the drawings.

The upsetter and punch are to be moved downward by a rod, h, to which a foot-treadle may be applied. A spring or other proper

means may be employed to effect the elevation of the upsetter and the punch.

The mechanism for feeding the eyelets to the eyelet-pin anvil consists of a chute or spout, B, and a supplying reservoir or hopper, C. Within the latter are two stationary brushes, i i, and a vibrating brush, k, the latter brush being carried by a lever, l, so connected with the chute as to be movable with and by it. These brushes serve to agitate the eyelets within the reservoir in order that they may pass into the discharging-ports. Leading from the hopper C into the chute is a series of ports or passages, m m m, the form of each of which in vertical section is shown in Fig. 6, each being wider at its bottom than at its top, and made so as to guide and direct an eyelet from the box into the chute only when the flange or wider part of the eyelet is lowermost. Under these circumstances each eyelet, when in the chute, will rest with its flange on the bottom of the chute, as shown in Fig. 6. The arrangement of each of the directing-ports, m m m, &c.—viz., with its wider end downward—is a feature which causes the eyelets to be properly delivered, flange downward, into the chute, no eyelet being able to escape from the hopper or reservoir C into the chute B unless the flange of the said eyelet may be downward.

The chute is to have reciprocating longitudinal movements imparted to it by means of mechanism consisting of a lever, n, which is connected to it by a bar, o, hinged both to the lever and the chute. The lower arm of the lever has a slot, p, into which a projection, q, from a wheel, r, enters. The said wheel has a notch, s, in its periphery. A spring-catch, t, formed as shown in Fig. 1, and carried by the treadle-rod h, operates in this notch while the rod may be in the act of rising upward, the operation being such as to cause the wheel to be rotated a short distance until the force of a spring, w, may overcome the hold of the said catch on the wheel and retract the wheel smartly. This will cause the chute to be moved backward from and afterward to be suddenly thrown toward and over the pin-anvil to the extent sufficient to carry the lowermost eyelet in the said chute directly upon the anvil. The said pin-anvil b has applied to it a spring-brake or friction-stopper, v, which, on depression of the pin c by the up-

setter *e*, will, by its friction or pressure against the pin, hold such pin down entirely below the upper surface of the anvil and prevent it from rising above the same. During the forward movement of the chute a cam, *w*, fixed on the lower end of the said chute, will be forced against the friction brake or stopper *v* and so as to press it away from the anvil-pin in a manner to enable the spring *d* of the said pin to elevate the pin through the eyelet, which will take place prior to the next retreat of the chute.

The spring brake or stopper *v*, the cam *w*, and the spring *d* constitute a mechanism not only for holding the anvil-pin down, as described, but for subsequently elevating or effecting the elevation of the said pin through an eyelet, in order that the eyelet may not only be received from the chute during and by retraction of such chute, but be centralized and be held in place on its anvil while such eyelet may be in the act of being fixed in a

piece of cloth or other material. A spring, *x*, at and over the discharging end of the chute, serves to keep the eyelets from falling out of the chute.

I claim—

1. The arrangement of one or more directing ports or passages, in manner substantially as described, with the hopper and chute of the eyeleting-machine.

2. A combination consisting of the following elements—viz., the eyelet-pin, a mechanism for feeding the eyelets to the pin, a mechanism which will perform the functions of holding the eyelet-pin down while an eyelet is being fed upon the pin-anvil and subsequently operating to elevate the eyelet-pin or effect its elevation through the eyelet, as specified.

JEREMIAH KEITH.
